UNITED STATES PATENT OFFICE.

JOSEPH D. GILLAN, OF PROVIDENCE, RHODE ISLAND, ASSIGNOR TO WARWICK STERLING COMPANY, OF PROVIDENCE, RHODE ISLAND, A CORPORATION OF RHODE ISLAND.

BUCKLE.

Specification of Letters Patent. Patented Apr. 16, 1918.

1,262,773.

Application filed December 7, 1915. Serial No. 65,625.

To all whom it may concern:

Be it known that I, JOSEPH D. GILLAN, a citizen of the United States, and resident of Providence, in the county of Providence and State of Rhode Island, have invented certain new and useful Improvements in Buckles, of which the following is a specification.

This invention relates to buckles for belts or similar articles and has for its object to provide such a buckle with a body portion having its sides bent up from the face thereof and a biting jaw pivoted intermediate its edges in said sides one of the edges of said 15 jaw being adapted to engage, grip, and bind one portion of the belt against the body portion of the buckle and a connector member to which the belt is attached, being pivotally connected to the opposite edge of 20 said jaw.

A further object of the invention is to provide means in the body portion for guiding the longitudinal motion of the connector member therein.

It is found in practice that where the biting jaw is rigidly attached to the connector member and the jaw engages a belt of unusual thickness, the connector is obliged to stand at an angle and project inwardly 25 against the body of the wearer which is both wrong in principle and uncomfortable to wear. To obviate this difficulty I have pivotally attached the connector member to the outer edge of the biting jaw and have guided 30 this connector member in the body portion whereby it may slide longitudinally therein in releasing the belt, or adjusting itself to 35 belts of different thicknesses.

Figure 1— is a front view representing 40 my improved buckle as attached to a belt.

Fig. 2— is a perspective view showing the inner side of the body portion of the buckle.

Fig. 3— is a perspective view of the connector member, which is pivotally connected 45 to the outer edge of the jaw member.

Fig. 4— is a front view of the biting jaw.

Fig. 5— is an edge view of the biting jaw.

Fig. 6— is a sectional side elevation of my improved buckle.

Fig. 7— is the same as Fig. 6, but illustrating the biting jaw as having been raised by a backward motion of the connector to release the belt.

Referring to the drawing 10 designates 55 the body portion of the buckle which is

preferably formed of sheet metal with its sides 11 and 12 bent up at substantially right angles to the front plate thereof. Two pairs of fingers 13 and 14 are formed integral with the opposite edges of these side walls and near opposite ends thereof. These fingers being bent inwardly toward each other serve as guiding means both for the belt and also for the connector as presently described.

In my improved type of belt buckle the belt is held by a gripping jaw 15 which is provided near its middle portion with a pair of pivoting pintles 16 which enter openings 17 in the sides of the body portion whereby this jaw is pivotally held between said walls to swing freely therein. One edge 18 of this jaw is slightly beveled, see Fig. 5 and is adapted to engage, grip, and bite one portion of the belt against the inner surface of the body portion and securely retain the same against slipping or being drawn outward.

The opposite or outer edge 19 of this biting jaw is also provided with pintles 20 which are engaged by ears 21 on the connector member 22. This connector member extends longitudinally along on the inner side of the body member as illustrated in Figs. 6 and 7 and its outer end 23 is connected to a loop 24 to which the end of the belt 25 is attached. A lip 26 is formed on the connector and is bent over backward and inward see Fig. 3 for the purpose of limiting the rearward swing of the biting jaw on its pivot 16, and the upper portion of this biting jaw is provided with a shoulder or rearwardly curved portion 27 adapted to engage this lip 26 to assist in serving as a stop for its rearward swing. By this arrangement the tongue is prevented from swinging so far back as to move out of operative position.

In the operation of my improved buckle the body portion is so constructed that it may be formed entirely of sheet metal and bent by purely mechanical operations into completed form and that without the use of solder.

Also by my improved construction both the connector 22 and the biting jaw 15 may be formed complete of sheet metal by bending or swaging into the desired form.

In assembling, first the jaw is pivotal mounted between the ears 21 in the co

necter, and then its pivots 16 are mounted in the eyes 17 of the side walls of the body portion. The connector now extends forward beneath the fingers 13 which permits free longitudinal action thereof, but limits the distance that the connector may be raised from the inner surface of the body portion.

In applying the buckle to the belt one end 25 of the belt is attached to the eye 24 of the buckle connector, the opposite end of the belt is passed around the body of the wearer and then between the walls 11 and 12 of the buckle and beneath the fingers 13 and 14, the portion 25 of the belt meanwhile being 15 pressed toward the biting jaw which causes the connector to tip this jaw into the position illustrated in Fig. 7, thereby permitting the end of the belt to be passed readily thereunder. It is only necessary now to release 20 the end 25 of the belt and the jaw immediately swings on its pivots 16 and causes its edge 18 to bite and secure the belt firmly in the body portion.

I have shown and described one construction 25 of my improved buckle but other details of construction may be employed without departing from the spirit and scope of my invention.

I claim:

30 1. A belt buckle comprising a sheet metal body member having integral sides bent at an angle thereto, a gripping jaw formed of a substantially straight piece of sheet metal having its ends provided with one set of pintles rotatably engaging said sides and a second set of pintles spaced from the first set, a connector member having ears with which the second set of pintles have rotative

engagement, said connector member having means for limiting pivotal movement of the gripping member in one direction.

2. A belt buckle comprising a sheet metal body member having integral sides bent at an angle thereto, a gripping jaw formed of a substantially straight piece of sheet metal 45 having its ends provided with one set of pintles rotatably engaging said sides, and a second set of pintles spaced from the first set, and a connector member having ears with which the second set of pintles have 50 rotative engagement, said connector member having means for limiting pivotal movement of the gripping member in one direction, said gripping member having an offset portion to coact with said movement-limiting 55 means.

3. A belt buckle comprising a sheet metal body member having integral sides bent at an angle thereto, a gripping jaw formed of a substantially straight piece of sheet metal 60 having its ends provided with one set of pintles rotatably engaging said sides and a second set of pintles spaced from the first set, and a connector member having ears 65 with which the second set of pintles have rotative engagement, said connector member having a lip overhanging the gripping member to limit pivotal movement of the gripping member in one direction.

In testimony whereof I affix my signature 70 in presence of two witnesses.

JOSEPH D. GILLAN.
